Primary Examiner — Katrina A Betton*(74) Attorney, Agent, or Firm* — Sheridan Ross P.C.(57) **CLAIM**

The ornamental design for a rack for a vehicle, as shown and described.

DESCRIPTION

FIG. 1 is a perspective view of a rack for a vehicle;
FIG. 2 is a top plan view thereof;
FIG. 3 is a bottom plan view thereof;
FIG. 4 is a front elevation view thereof;
FIG. 5 is a rear elevation view thereof;
FIG. 6 is a right elevation view thereof;
FIG. 7 is a left elevation view thereof; and,
FIG. 8 is a perspective view thereof interconnected to a vehicle.

The broken lines are included for the purpose of illustrating environment and form no part of the claimed design.
